VENETIAN BLIND STRUCTURE

Morris L. Duskin and Herbert L. Magill, Chicago,
III.

Application January 6, 1937, Serial No. 119,184

17 Claims. (Cl. 156—17)

This invention relates to Venetian blinds. One object of the invention is to provide a blind of this type adapted to be made of durable moisture-proof materials so as to be readily cleanable and to resist deterioration. Another object is to provide a Venetian blind with supporting straps adapted to include ornamental color panels which may be changed at will to secure various decorative color schemes. Other objects will appear as the description proceeds. The invention consists in various features and elements of construction in combination, as herein shown and described and as indicated by the claims.

In the drawing:

15. Figure 1 is a face view elevation of a portion of a Venetian blind constructed in accordance with this invention, the upper supporting structure being omitted, and the middle portion of the blind being broken away to condense the view.

Figure 2 is a plan view of one of the slats.

Figure 3 is a detail section taken as indicated at line 3—3 on Figure 1, showing the slats in section and one pair of supporting straps in side elevation.

Figure 4 is a detail elevation looking in the direction of arrows, 4—4, on Figure 3.

Figure 5 is a view similar to Figure 4, on a larger scale, and showing connected portions of the slats in section.

Figure 6 is a detail section taken as indicated at line 6—6 on Figure 5.

Figure 7 is a detail section taken as indicated at line 7—7 on Figure 5.

Figure 8 is a detail section taken as indicated at line 8—8 on Figure 5.

Figure 9 is a side view of the pair of links shown in Figure 5, and taken partly in section, as indicated at line 9—9 on said Figure 5.

Figure 10 is a detail perspective view of a spring catch device.

The usual construction for Venetian blinds includes flat wooden slats and supporting tapes of fabric connected by cross-tapes on which the slats are removably lodged, and which serve for tilting them to various degrees of inclination, as controlled by the manipulation of the tapes from the supporting structure above. This invention undertakes to supply an improved form of slat which may be constructed of sheet metal, and to supply a more durable and cleanly form of strap which may also be made of metal. To render these straps sufficiently flexible to permit collapsing the blind in the usual manner, they are constructed of a series of rigid links pivotally

connected or hinged together so that they will fold up when the slats are lifted by supporting means independent of the straps for collapsing the blind in the usual manner. In addition, these hinged links may be fitted with removable panels of colored material,—preferably some synthetic composition,—so that the straps may serve to add a decorative touch to the blind, which may be varied by changing the panels of one color for those of another, when desired.

10 In the drawing, Figure 1 shows a portion of a Venetian blind comprising slats, 1, connected by supporting straps each consisting of links, 2 and 3. As seen in Figure 2, each slat, 1, has its longitudinal margins formed into tubular beads, 4, 15 which may be interrupted by notches, 5, cutting through the beads, preferably near the ends of the slat to accommodate the supporting straps or chains. The links, 3, of the straps include laterally projecting pivot studs or pintles, 6, which 20 extend into the tubular beads, 4, for pivotally connecting the slats, 1, to the supporting straps.

In each supporting strap or chain the links, 3, alternate with the links, 2, so that one link of each type constitutes a pair extending between 25 consecutive slats, 1, 1. Each link, 2, includes side bars, 7, 7, and in the form shown these side bars are connected permanently by a cross-bar, 8. At their ends the side bars are formed with terminals, 9, which are apertured for pivotal connection with the adjacent links, 3.

Each of the links, 3, includes side bars, 10, 10, which, in the form shown, are not connected to each other but are held apart in spaced relation by a panel or filler, 11, which may be of any 35 suitable material, and is preferably made of some such synthetic material, as Catalin, Pyrolin, Bakelite, Celluloid, or some similar compound, which may be molded in the desired shape. The side bars, 10, 10, are formed with terminals, 12, 40 adapted to interlap the terminals, 9, of the links, 2, and said terminals include laterally projecting pivots to engage the apertures of the terminals, 9. At one end of the link, 3, the pivots, 13, are only long enough to extend into the terminals, 9, of the next link, 2, but at the other end the pivots, 6, are long enough to extend through the terminals, 9, and into the adjacent ends of the tubular bead, 4, of a slat, 1. If the desired proportions of the bead, 4, are such as to render it too large to 50 fit snugly over the pivots, 6, the end portions of the bead adjacent the notch, 5, may be formed to a smaller diameter, as seen at 14 in Figure 5.

In assembling the parts the terminal lugs, 9, 9, of one of the links, 2, will be positioned in a notch,

5, of a slat, 1, with the apertures of the lugs, 9, aligned with the tubular terminals, 14, of the bead, 4. Then the two side bars, 10, 10, of a link, 3, will be moved into position carrying their pivots, 6, through the apertured lugs, 9, and into the bearing tubes, 14. At the same time, at the opposite ends of the bars, 10, 10, their pivots, 13, will be fitted into the terminal lugs, 9, of another link, 2. Then the filler block or panel, 11, is inserted between the bars, 10, 10, to hold them apart in proper relation to the adjacent links, 2, 2. For holding the panel, 11, in position it is provided with spring detent devices which may be constructed of spring sheet metal formed, as shown 15 in Figure 10, each with a cylindrical body portion, 15, adapted to fit into a bore, 16, formed in the edge of the panel or filler block, 11. A bent spring arm, 17, at the end of the cylindrical body, 15, terminates in a rounded boss, 18, which stands 20 normally above the edge surface of the block, 11, but may be sprung inwardly into the recess which is a part of the bore, 16. Each block, 11, may be provided with four of these detents, and each of the side bars, 10, of the link, 3, is formed with 25 recesses, 19 and 20, respectively, (see Figures 7 and 8) near its opposite ends, adapted to be engaged by the bosses, 18, of these detent devices when the filler, 11, is inserted between the bars, 10, 10. The filler block is thus held removably 30 in position and serves to hold the side bars, 10, in place so that their pivots, 6 and 13, shall remain engaged with the terminals, 9, of the adjacent links, 2, and with the bearing portions, 14, of the bead, 4.

35 The link, 2, may also have a filler block or panel, as seen at 21, but since the side bars, 7, 7, are shown permanently connected by the cross-bar, 8, the function of the filler, 21, is primarily decorative. It may be secured in place by forming the 40 inner faces of the side bars, 7, with channels of V-shaped cross-section, as seen in Figure 6 at 22, and correspondingly forming the edges of the panel, 21, so that it can be slidably inserted between the bars, 7, from the open end of the link 45 before the next link, 3, is assembled therewith.

50 A strap or chain made up of links, 2 and 3, as just described, and connected at intervals to the slats, 1, takes the place of the usual fabric straps or tapes employed in Venetian blind structures for connecting the consecutive slats and supporting them in the extended position of the blind. For collapsing the blind to draw it clear of the window there is included a bottom bar, 23, which may be simply the bottom slats of the series, suspended by cords or wires, 24, which pass through suitable apertures, 25, in each of the slats, and which are preferably positioned so as to register with the connecting straps or chains composed of links, 2 and 3, so as to be concealed from view.

55 Any suitable winding or operating gear, mounted at the top of the window and not shown herein, serves to draw the cords, 24, upward, thus elevating the bottom member, which picks up the slats, 1, as it rises and collects them in a closely piled formation, as seen in the lower portion of the view in Figure 1, and also in Figure 3. To permit this close piling of the slats, 1, the links, 2 and 3, connecting each pair of adjacent slats, 1, must fold upon each other, as seen in Figure 3.

60 To insure that they will fold automatically and in a definite direction, the interlapping terminals, 9, at the pivots, 13, are formed with flat surfaces, 26, which abut corresponding flat surfaces, 27, on the side bars, 10, so as to prevent the unfolding of adjacent links, 2 and 3, into strict align-

ment, and to limit them to the angular relation seen in Figures 3 and 9. Thus, when the links are caused to fold by the lifting of the slats, 1, the initial angle between links, 2 and 3, will merely be reduced, causing the pivots, 13, to move 5 outward—that is, away from the beaded edges of the slats, 1, until the links, 2 and 3, can collapse upon each other in substantially horizontal position, as seen in Figure 3. The terminals, 9 and 12, at which links, 2 and 3, are joined on 10 the pivots, 13, are offset with respect to the side bars, 7 and 10, so that the faces of these bars, which will meet in the folded position, lie in planes extending through the axis of the pivot, 13, and will thus swing into a common plane when 15 the bars are folded. As indicated in Figure 3, the straps or chains at opposite sides of the blinds are arranged to fold oppositely so that the links, 2 and 3, in collapsed position are disposed outside the vertical planes between which the 20 slats, 1, are included.

To insure a pleasing and relatively simple appearance in the finished Venetian blind employing these features, the curved outlines of the terminal lugs or ears, 9 and 12, of the links may 25 be of the same diameter as the beads, 4, and will be accurately aligned therewith; and the filler blocks, 11, will be formed at their ends with cylindrically curved portions, 28 and 29, also of the same diameter as the beads, 4, and axially 30 aligned therewith. Thus the horizontal lines defined by the beads, 4, of the slats, will be carried across the vertically extending straps or chains without substantial interruption, and, if desired, the parts, 4 and 11, may be similarly 35 colored so as to give the effect of continuous horizontal stripes in the structure.

It may be understood that when the slats, 1, are formed of sheet metal they may be of any desired non-corrosive composition, or may be 40 given a non-corrosive finish as by electro-plating or by means of a suitable enamel, and that the metallic link structures, 2 and 3, may also be of such composition or finish as to avoid corrosion or rust. The filler blocks, 11 and 21, if made of 45 any of the materials suggested, will be moisture-proof, and practically impervious to dust, so that they can be readily cleaned when required. Ordinary dusting and occasional treatment with a damp cloth will thus keep the blind indefinitely 50 in an attractive and cleanly condition.

The method of construction permits of readily disassembling the parts for substituting filler blocks, 11 and 21, of a different color, if desired, or for changing the slats, 1, to those of a different 55 finish, if occasion arises, for altering the color scheme. As indicated in Figures 2 and 3, the slats may be reinforced adjacent the notches, 5, if desired, by forming upwardly projecting ribs, 30, in their flat surfaces to insure perfect alignment of the end portions of the beads, 4, with the intermediate parts.

While there is shown and described herein certain specific structure embodying the invention, it will be manifest to those skilled in the art that 65 various modifications and re-arrangements of the parts may be made without departing from the spirit and scope of the invention, and that the same is not limited to the particular form herein shown and described, except in so far as indicated by the appended claims.

We claim:

1. In a Venetian blind structure a series of slats composed of sheet metal and each having its longitudinal margins shaped to form tubular 75

beads, each slat having notches cut through said beads, and supporting straps accommodated in said notches, each strap comprising a series of rigid links hingedly connected, end to end, with laterally projecting pivots engaged in the beads of the slats.

2. In a Venetian blind structure as defined in claim 1, separate straps engaged with the beads at opposite margins respectively of the slats, and each strap being composed of links in pairs with a pair extending between adjacent slats of the blind, the hinge joints of each pair intermediate their connections with the slats including means limiting the relative movement of adjacent links to permit their folding or collapse in one direction only, the joints of said separate straps at opposite edges of the slats being adapted to collapse in opposite directions.

3. In a Venetian blind structure as defined in claim 1, said links including terminal portions of a contour axially aligned with the tubular beads of the slats and of the same shape so as to appear as substantially continuous therewith.

4. In a Venetian blind structure as defined in claim 1, the links of said straps each comprising a pair of side bars and an interposed filler, the ends of said side bars and of said fillers occupying the notches of the slats being co-axial with the tubular beads of the slats and of the same shape in cross-section.

5. In a Venetian blind structure, a series of slats, and supporting straps each composed of a series of rigid open links hingedly connected, means connecting said slats to the straps, and ornamental filler panels fitted removably in the openings of the links to produce a decorative effect.

6. A strap for a Venetian blind comprising a series of links hingedly connected end to end, each link comprising a pair of side bars spaced apart with a filler block secured between them, said bars having terminal portions formed for the pivotal inter-connection of adjacent links with the terminals of one link disposed between the terminals of the next link whereby the filler block of the first mentioned link serves to maintain the pivotal connection of said terminals.

7. A strap for a Venetian blind comprising a series of links hingedly connected end to end, each link comprising a pair of side bars spaced apart with a filler block secured between them, said bars having terminal portions some of which are apertured and others of which are provided with pivots to engage such apertures, the filler blocks of alternate links serving to maintain such pivotal engagement.

8. A strap for a Venetian blind comprising a series of links hingedly connected end to end, each link comprising a pair of side bars spaced apart with a filler removably secured between them, the side bars of alternate links being permanently joined by a cross-bar, and having terminals apertured for connection with the side bars of intermediate links, each intermediate link having its side bars provided with outwardly projecting pivot studs at their terminals, whereby the filler serves to hold said bars apart with their pivots engaging the apertured terminals of the said alternate links.

70 9. A strap for a Venetian blind comprising a series of links hingedly connected end to end, each link comprising a pair of side bars spaced apart with a filler removably secured between them, the side bars of alternate links being permanently joined by a cross-bar, and having ter-

minals apertured for connection of the side bars with intermediate links, each intermediate link consisting of side bars with outwardly projecting pivot studs at their terminals whereby the filler serves to hold said bars apart with their pivots engaging the apertured terminals of the said alternate links, the pivot studs at one end of each of said intermediate links extending through and laterally beyond the terminals of the connected link for engaging a slat of the blind.

10 10. In a Venetian blind structure, a series of slats composed of sheet metal and each having its longitudinal margins shaped to form tubular beads, each slat having notches cut through said beads and supporting straps accommodated in said notches, each strap being composed of rigid links hingedly connected end to end, and each alternate link comprising a pair of side bars spaced apart with a filler removably secured between them, the other links including apertured terminals adapted to lap the ends of said side bars, and the side bars having outwardly projecting pivot studs extending through the apertures of said terminals and into the tubular beads adjacent the notches of the slats.

15 11. In the construction defined in claim 6, spring detents disposed for removably securing said filler blocks in place between the side bars of the links.

20 12. In the construction defined in claim 6, the opposing faces of the side bars having recesses and the filler blocks being provided with spring detents adapted to engage said recesses when the filler blocks are positioned between the side bars.

25 13. In a Venetian blind structure, a series of slats each composed of sheet material with its longitudinal margins shaped to form tubular beads, said slats having notches cut through said beads, supporting straps each composed of a series of rigid links hingedly connected, and pivotal means projecting laterally at alternate hinge joints of each strap and directly engaging in the open ends of the tubular bead of a slat at opposite sides of the notch therein.

30 14. In a Venetian blind structure, a series of slats each formed with marginal beads notched to accommodate supporting straps, and straps each composed of a series of rigid links hingedly connected, together with pivot means each co-axial with a hinge connection of the links and projecting laterally into direct pivotal engagement with a longitudinal bead of the slat at opposite sides of the notch therein.

35 15. In a Venetian blind structure, a series of slats each formed with marginal beads notched to accommodate supporting straps, and straps each composed of a series of rigid links hingedly connected, together with pivot means each co-axial with a hinge connection of the links and projecting laterally into direct pivotal engagement with a longitudinal bead of the slat at opposite sides of the notch therein, each pair of adjacent slats being connected by two links of a strap, and the hinge connecting the two links including features which limit the relative movement of the links and permit their folding for collapse in one direction only so as to carry said links and their connecting hinge outwardly away from the vertical plane of the blind.

40 16. In a Venetian blind structure, a series of slats notched at their edges to accommodate supporting straps, and straps each composed of a series of rigid links hingedly connected, with pivotal means at each alternate hinge connection

of the strap projecting laterally into pivotal engagement with a slat at opposite sides of the notch therein.

17. In a Venetian blind structure, a series of slats each composed of sheet material with a longitudinal margin shaped to form a tubular bead, said margin being notched to accommodate a supporting strap, and a strap composed of a

series of rigid links hingedly connected, with pivot means at each alternate hinge connection projecting laterally into the tubular bead of a slat at opposite sides of the notch for directly connecting the slat to the strap.
